DOOR LIFTING MECHANISM

Thorvald Madland, Chicago, Ill., assignor to The Youngstown Steel Door Company, Cleveland, Ohio, a corporation of Ohio

Application January 5, 1944, Serial No. 517,004

5 Claims. (Cl. 16—99)

This invention relates to door lifting mechanisms particularly adapted for sliding doors of railway house cars.

It is an object of this invention to provide a lifting mechanism for sliding car doors which shall lie within the most critical tunnel clearance diagram and thereby create a standard lifting mechanism applicable to cars of different widths.

A further object is to provide lifting mechanism of the character set forth above which shall be operable in either direction in a plane parallel to the doors.

Other objects of the invention will become clear as the description thereof proceeds.

In the drawing forming part of this specification:

Fig. 1 is a fragmentary elevation of a sliding car door equipped with one embodiment of the instant invention, parts being broken away in order to more clearly show the invention.

Fig. 2 is a view similar to Fig. 1 illustrating another embodiment of the invention.

Fig. 3 is a vertical section taken on line 3—3 of Fig. 2.

Fig. 4 is a vertical section taken on line 4—4 of Fig. 1.

Fig. 5 is a vertical section taken on line 5—5 of Fig. 1.

Fig. 6 is a horizontal section taken on line 6—6 of Fig. 1.

Referring to the drawing and more particularly to Figs. 1, 4, 5, and 6 illustrating one embodiment of the invention, the numeral 10 designates a sliding door for railway house cars. The door may be of any desired construction but as illustrated is formed of a metallic panel 11 provided with spaced horizontal corrugations, one of which is indicated at 12. The front vertical margin of the door is reinforced by means of front and rear members 13 and 14 and the rear vertical margin of the door is reinforced by means of front and rear members 15 and 16.

The lower margin of the metallic panel 11 is offset outwardly as indicated at 17. A metallic backing plate 18 is secured to the panel 11 in substantially the main plane thereof above the outwardly offset portion 17 and extends downwardly and is secured to the depending flange 19 of a Z-shaped reinforcing member, the web 20 of which extends outwardly and the flange 21 upwardly. This flange lies inwardly of and is fastened to the outwardly offset portion 17 of the panel as by means of rivets 22. The construction of the lower portion of the door as described

above is more clearly illustrated in Fig. 4 of the drawing and provides a box section adapted to receive the door lifting mechanism of the instant invention.

5 The lifting mechanism of the considered embodiment of the invention comprises spaced bracket members 23—23 which, as more clearly shown in Fig. 5 of the drawing, embodies a substantially Z-shaped plate 24 having an upstanding flange 25 disposed between and secured to the panel 11 and the backing plate 18. The web 26 of the Z-shaped plate 24 slopes downwardly and outwardly in conformity with the slope of the lower portion of the panel and terminates in a depending flange 27. Each of the bracket members 23 comprises also a channel-shaped member 28 having a web 29 disposed in laterally spaced relationship to the depending flange 27, outwardly directed legs 30—30 and oppositely extending flanges 31—31 which abut against the depending flange 27 of the Z-shaped member 24 and which are fastened together therewith to the panel 11 as by means of rivets 32.

Each of the bracket members 23 carries a roller 33 disposed within the space between the web 29 and the flange 27 and supported by means of a pin 34 carried by said web and said flange.

Main door rollers 35—35 are positioned below the bracket members 23—23. Each of the rollers 35 is carried by means of a housing member 36 which, as more clearly illustrated in Fig. 5 of the drawing, is substantially channel-shaped in section. Each roller is carried by the housing member 36 by means of a pin 37 extending through 35 a roller bearing 38 of the roller and beyond the walls 39 and 40 of the housing member for a purpose which will hereinafter appear.

The upper wall of each of the roller housing members 36—36 is in the form of a cam 41, as 40 more clearly shown in Figs. 1 and 5 of the drawing and is disposed below a roller 33 and adapted for engagement therewith.

The ends of the pins 37 of the main rollers are adapted to extend into guides 42 and 43, as more 45 clearly shown in Figs. 1 and 5 of the drawing. The guide 42 is provided by a slot 44 extending downwardly through the upper edge of the upstanding flange 21 of the bottom Z-shaped door reinforcing member. The guide 43 is provided by a corresponding slot 45 extending downwardly through the upper edge of the web 46 of a substantially channel-shaped member, the side walls 47 and 48 of which are directed outwardly and formed with attaching flanges 49 and 50 secured 50 to the upstanding flange 21.

Operation of the roller housing members 36-36 is obtained by means of an actuating member 51 journalled in outer and inner bearing plates 52 and 53, as more clearly shown in Figs. 4 and 6 of the drawing. The actuating member 51 extends outwardly of the door 10 and is reduced in section as indicated at 54. An operating lever 55 is secured upon the reduced section of the actuating member.

The actuating member 51 is formed with oppositely extending spaced ears 56-56 and 57-57. Connecting bars 58 and 59 pivotally secured as indicated at 60-60 to the roller housing members 36-36 extend between the ears 56-56 and 57-57 and are pivotally connected thereto by means of the pins 61-61. As more clearly shown in Fig. 1, the actuating member 51 is disposed intermediate the roller housing members and by reason of the above described construction is operable to impart movement to the roller housing members toward each other by operation of the lever 55 in either direction in a plane parallel to the door.

As shown in Fig. 1 and more particularly in Fig. 4, the offset portion 17 of the panel is recessed as indicated at 62 so that the operating lever 55 does not lie substantially outwardly of the offset portion 17. The lifting mechanism is accordingly adapted to be disposed within the most critical tunnel clearance diagram and thereby adapted for use upon railway house cars irrespective of their width.

In its lowered position, the door is adapted to be frictionally supported by means of the web 20 of the bottom Z-shaped door reinforcing member upon a track 63 carried by the car under-frame 64 by means of a plurality of brackets, one of which is indicated at 65. In order to support the door upon the main rollers 35-35 so that it may easily be moved upon the track the operating lever 55 may be moved in either direction in a plane parallel to the door. Such movement of the lever imparts rotation to the actuating member and movement to the connecting bars 58 and 59 which in turn cause the roller housing members 36-36 to rock about the main rollers 35-35 toward each other. During the rocking movement of the housing members 36-36 the upper cam-shaped walls thereof engage and roll under the rollers 33-33, thereby causing the door to be lifted above the track 63. The main rollers 35-35 are maintained in position and the door is permitted to rise relative to the main rollers by the association between the ends of the pins 37-37 and the guides 42-42 and 43-43. When the door is elevated, its weight is transferred to the main rollers upon which it may easily be moved upon the track. Upon release of the operating lever the door gravitates downwardly until frictional engagement is again established between the web 20 and the track 63.

Another embodiment of the invention is illustrated in Figs. 2 and 3 of the drawing. This embodiment utilizes much of the construction hereinabove described in connection with the first considered embodiment of the invention as clearly appears from the drawing. However, in place of the bracket members 23-23 the considered embodiment of the invention utilizes bracket members 66-66 angular in shape and having an upstanding leg 67 disposed between and secured to the panel 11 and backing plate 18 and an outwardly directed leg 68. The legs 67 and 68 are preferably reinforced by means of a web 69.

The main rollers 35-35 are carried by means

of housing members 70-70 through the agency of pins 71-71 which extend beyond the walls 72-72 of the housing members and into the guides 42 and 43 formed as hereinabove described. The walls 72-72 of the housing members 70-70 are connected by means of a web 73. Rollers 74-74 are rotatably mounted between the walls 72-72 by means of pins 74-74 and are so disposed as to lie below and be adapted to roll against the outwardly extending legs 68-68 of the bracket members 66-66. As more clearly appears from Fig. 2 of the drawing, the housing members 70-70 are inclined upwardly in opposite directions relative to each other.

15 In its lowered position the door is adapted to be supported frictionally upon a track 63. To elevate and support it upon the main rollers 35-35 the operating lever 55 is moved in either direction in a plane parallel to the door to impart 20 rotation to the actuating member 51 and movement of the connecting bars 58 and 59 toward each other. Such movement of the connecting bars imparts rocking movement to the housing members 70-70 toward each other and during 25 this movement the rollers 74-74 bear and roll against the outwardly extending legs 68 so as to lift the door. The door is then supported upon the main rollers and may be moved in either direction upon the track. Release of the operating 30 lever at any position of the door will be followed by downward movement of the door into frictional engagement with the track.

It will be apparent that numerous changes and modifications in the details of the invention 35 will be clear to those skilled in the art. It is intended, therefore, that all such modifications and changes be comprehended within this invention, which is to be limited only by the scope of the claims appended hereto.

40 I claim:

1. A lifting mechanism for a sliding door comprising spaced brackets secured to said door, spaced roller housings, main rollers, pins rotatably mounting said rollers in said housings, the 45 ends of said pins extending beyond said housings, auxiliary rollers carried by said housings above said main rollers, said auxiliary rollers lying below and adjacent to said brackets, members on said doors, guideways in said members, said ends 50 of said pins extending into said guideways and means for rocking said housings relative to said main rollers, said auxiliary rollers having rolling bearing against said brackets during rocking movement of said housings to lift said door.

55 2. A lifting mechanism for a sliding door comprising spaced brackets secured to said door, spaced roller housings, main rollers, pins rotatably mounting said rollers in said housings, the ends of said pins extending beyond said housings, auxiliary rollers carried by said housings above said 60 main rollers, said auxiliary rollers lying below and adjacent to said brackets, members on said door, guideways in said members, said ends of said pins extending into said guideways and means 65 for rocking said housings relative to said main rollers, said auxiliary rollers having rolling bearing against said brackets during rocking movement of said housings to lift said door, said means embodying bars pivotally fastened to said housings above said main rollers, an actuating member journalled in said door between said housings, said bars being pivotally fastened to said actuating member, and an operating lever mounted on said actuating member.

70 3. A lifting mechanism for a sliding door com-

prising spaced brackets secured to said door, substantially horizontal flanges on said brackets, spaced oppositely inclined roller housings, main rollers, pins rotatably mounting said rollers in said housings, the ends of said pins extending beyond said housings, auxiliary rollers carried by said housings above said main rollers, said auxiliary rollers lying below and adjacent to said flanges, members on said door, guideways in said members, said ends of said pins extending into said guideways and means for rocking said housings toward each other relative to said main rollers, said auxiliary rollers having rolling bearing against said flanges during rocking movement of said housings to lift said door.

4. A lifting mechanism for a sliding door comprising spaced brackets secured to said door, auxiliary rollers carried by said brackets, spaced roller housings having walls inclined to the horizontal, main rollers carried by said housings, pins extending through said housings and main rollers, the ends of said pins projecting beyond said housings, members on said door, guideways

in said members, said ends of said pins extending into said guideways and means for rocking said housings relative to said main rollers, said inclined walls having rolling bearings against said auxiliary rollers during rocking movement of said housings to lift said door.

5. A lifting mechanism for a sliding door comprising longitudinally spaced bracket members secured to said door, longitudinally spaced roller housing members, main rollers carried by said housing members, pins extending through said housing members and said main rollers, the ends of said pins projecting beyond said housing members, guideways on said door, the ends of said pins extending into said guideways, auxiliary rollers carried by certain of said members, and means for rocking said housing members relative to said main rollers, said auxiliary rollers having rolling bearing against the others of said members during rocking movement of said housing members to lift said door.

THORVALD MADLAND.
